UNITED STATES PATENT OFFICE.

MORRIS J. LOVETT, OF RANDSBURG, CALIFORNIA.

PERMUTATION-PADLOCK.

1,028,754.

Specification of Letters Patent.

Patented June 4, 1912.

Application filed October 23, 1911. Serial No. 656,149.

To all whom it may concern:

Be it known that I, MORRIS J. LOVETT, a citizen of the United States, residing at Randsburg, in the county of Kern and State 5 of California, have invented a new and useful Permutation-Padlock, of which the following is a specification.

It is the object of the present invention to provide, in a permutation pad-lock, a novel 10 means for operatively connecting the shackle with the tumblers.

A further object of the invention is to provide novel means for changing the combination of the padlock.

15 A further object of the invention is to provide novel means for controlling the sliding movement of the shackle.

The invention aims, moreover, to improve generally, and to increase the utility of, 20 devices of that class to which the present invention appertains.

With the foregoing and other objects in view, which will appear as the description proceeds, the invention resides in the combination and arrangement of parts and in the details of construction hereinafter described and claimed, it being understood that changes in the precise embodiment of invention herein disclosed can be made without 25 departing from the spirit of the invention.

In the accompanying drawings,—Figure 1 shows in elevation, one of the parts of the casing of a lock, the operative elements 30 of the lock being shown in place in this part of the casing; Fig. 2 is a side elevation of the lock, parts being sectioned; Fig. 3 is a transverse section upon the line 3—3 of Fig. 1, parts appearing in elevation; Fig. 40 4 is an elevation of one of the tumblers; Fig. 5 is a fragmental perspective of the shackle and of the finger which is carried by the shackle; and Fig. 6 is a fragmental perspective of one end of the shackle controlling spring.

45 In carrying out the invention there is provided a casing 1, preferably comprising distinct parts 2, united by countersunk rivets 3, or in any other suitable manner, the rivets 3 registering in openings 4 in the parts 2. The parts 2 are duplicates, and but one of them will be described, it being understood without further explanation, that the description applies with equal propriety to both parts 2.

Each part 2 is equipped in its upper edge

with a seat 5, adapted to receive the free end of the shackle. Extended longitudinally of the inner face of the part 2 is a shackle-receiving groove 6, communicating with a laterally extending spring space 7, the space 7 flaring as it approaches and enters the shackle-receiving groove 6. The spring space 7 in its uppermost portion communicates with a stop opening 8, extended about the shackle-receiving groove 6 and communicating therewith. At its lower end, the shackle-receiving groove 6 communicates with a rectangularly disposed finger chamber 9, the finger chamber 9 at its inner end communicating with an enlarged tumbler compartment 10, located parallel to the shackle-receiving groove 6 and extended toward the top of the casing 1. At the sides of the tumbler compartment 10 are bearing 70 grooves 11, disposed at right angles to the shackle-receiving groove 6.

When the two parts 2 of the casing 1, constructed as above described, are bound together by the securing rivets 3, the tumbler shaft 12 is journaled for rotation in the bearing grooves 11, the shaft extending through the tumbler compartment 10. If desired, a supplemental bearing 14, located in the tumbler compartment 10, and connected with one of the parts 2, may receive for rotation, the inner end of the tumbler shaft 12, although the provision of this bearing 14 is a matter of secondary consequence. Mounted to rotate upon the tumbler shaft 80 12 and located within the tumbler compartment 10, are tumblers 15 and 16, provided with spacing hubs 17, there being interengaging, lateral projections 18 upon the tumblers 15 and 16. The tumblers 15 and 16 85 are peripherally notched, as shown at 19 in Fig. 4, in connection with the tumbler 16, the relative positions between the notches 19 and the projections 18 being fixed as the taste of the manufacturer may direct.

The outer end of the tumbler shaft 12 is threaded as shown at 20, to receive a nut 21, adapted to clamp a tumbler 22 against a shoulder 23 which is fixed upon the tumbler shaft 12. Since the tumbler 22 is secured 105 to the tumbler shaft 12, this tumbler may be considered as the fixed tumbler, the tumblers 15 and 16, which are rotatable upon the tumbler shaft 12, being considered as the movable tumblers. The fixed tumbler 22 and 110 the movable tumbler 16 are equipped with interengaging lateral projections 24. The

fixed tumbler 22 is peripherally notched, as will be readily understood from an inspection of Fig. 1, the notch 19 in the tumbler 16 serving to illustrate with equal propriety, the notch in the periphery of the fixed tumbler.

Secured to the outer, protruding end of the tumbler shaft 12 is a graduated dial 25, adapted to coöperate with the dial 26 formed upon the outer face of the casing 1, the dials 25 and 26 being graduated in any desired manner. The extremity of the tumbler shaft 12 terminates in an operating knob 27.

The shackle, denoted generally by the numeral 28 is mounted for rotation and for longitudinal sliding movement in the mating shackle-receiving grooves 6. The free end 29 of the shackle 28 is received within the mating seats 5, when the shackle is in locked position. Pivotaly connected with the lower extremity of the shackle 28, as shown, at 30, is a rectangularly disposed finger 31. The shackle 28 is adapted to rotate in the finger 31, but when the shackle 28 is moved longitudinally, the finger 31 will move transversely, along with the shackle. The finger 31 is housed in the finger chamber 9 and protrudes across the tumbler compartment 10. When the shackle 28 is drawn upwardly, the finger 31 will enter the notches 19, in the tumblers 15, 16 and 22, when the notches are alined in a manner to be described hereinafter. Under such circumstances, the end 29 of the shackle 28 may be withdrawn from the seat 5, permitting the shackle 28 to be swung into the open position shown in Fig. 1. When, however, the shackle is thrust downwardly, to remove the finger 31 from the grooves 19 in the tumblers 15, 16 and 22, the end 29 of the shackle 28 will be held in the seat 5, when the tumblers 15, 16 and 22, or any one of them, is rotated so that the periphery of one tumbler, instead of the notch 19 of such tumbler, engages with the finger 31.

The shackle 28 is provided with a circumscribing groove 32, adapted to receive one end 33 of a spring plate 34, the opposite end of which is wedged and bound in the diminished end of the spring space 7. The shackle 28 is equipped with a radial lug 35 which is adapted to enter the annular stop opening 8.

In practical operation, the knob 27 is seized, and the tumbler shaft 12 is rotated, the tumbler shaft carrying with it, in its rotation, the fixed tumbler 22. The interengaging elements 24 of the tumblers 22 and 16 and the interengaging elements 18 of the tumblers 16 and 15 will cause the notches 19 in all of the tumblers to be alined, this alining of the notches 19 in the several tumblers being readily secured by noting the proper combinations upon the dials 26 and 27. This operation is common and well

known, and need not be entered into specifically, so far as describing any particular combination is concerned.

The shackle 28 is normally held in locked position by reason of the fact that the peripheries of the tumblers 22, 16 and 15 engage the finger 31 and hold the end 29 of the shackle 28 in the seat 5. When, however, the notches 19 in the several tumblers are alined, in the manner hereinbefore described, the shackle 28 may be lifted, the finger 31 moving into the alined notches of the tumblers, and the end 29 of the shackle 28 being withdrawn from the seat 5, whereupon the shackle may be rotated into the open position shown in Fig. 1. When the shackle 28 is lifted, to remove the end 29 from the seat 5, the spring 34 will be put under tension. At the same time, when the shackle 28 is rotated, the lug 35 of the shackle 28 will pass into the stop opening 8 and hold the shackle 28 elevated.

When it is desired to place the device in locked position, the shackle 28 is rotated from the position shown in Fig. 1, until the end 29 of the shackle 28 is above the seat 5, whereupon, when the shackle 28 moves downwardly, the lug 35 will ride out of the stop opening 8 and pass into the spring space 7, the spring 34 acting to thrust the shackle 28 downwardly, into a locked position. This movement of the shackle 28 will depress the finger 31 out of the alined notches 19 in the tumblers 22, 16 and 15, whereupon if the tumbler shaft 12 be given a turn or two, in either direction, one or all of the tumblers 22, 16 and 15 will be rotated, so that their notches 19 are no longer alined. The finger 31 will thus be held in the position to which it has been moved by the action of the spring 34, and the end 29 of the shackle will be held in the seat 5.

As will be readily understood, the combination may be changed by loosening the hold of the nut 21 upon the tumbler 22, whereupon the tumbler 22 may be rotated into any desired position upon the tumbler shaft 12. Subsequently, the nut 21 may be rotated to bind the tumbler 22 in its adjusted position, against the shoulder 23. Noting the relatively large number of graduations upon the dials 25 and 26, it will be understood readily that a great variety of combinations may thus be effected.

Having thus described the invention, what is claimed is:

1. A permutation pad-lock comprising a casing; a shackle slidable and rotatable in the casing; a finger mounted upon the shackle to slide with the shackle, the shackle being rotatably connected with the finger and the finger being held against rotation with the shackle, by the casing; and a tumbler mounted for rotation in the casing, the tumbler having an opening in which the

finger moves transversely; the finger co-operating with the casing to maintain one end of the shackle permanently in the casing.

5 2. A permutation pad-lock comprising a casing; a shackle slideable and rotatable in the casing; a finger mounted upon the shackle to slide with the shackle, the shackle being rotatably connected with the finger, 10 and the finger being held, by the casing, against rotation with the shackle; a tumbler mounted for rotation in the casing and having an opening to receive the finger; and spring means engaging the shackle, to move 15 the finger out of the opening.

3. A permutation pad-lock comprising a casing having a shackle-receiving opening, the casing being provided with a spring space, communicating with the shackle-receiving opening, there being a stop opening 20 communicating with the shackle-receiving

opening and with the spring space; a shackle mounted to slide and to rotate in the shackle-receiving opening; a spring mounted in the spring space and engaged at one end with 25 the shackle to slide the same, there being a lug upon the shackle, adapted to register in the stop opening, to hold the shackle against sliding movement and to maintain the spring under tension; a tumbler mounted to 30 rotate in the casing and provided with an opening; and means carried by the shackle for engagement by the tumbler and for registration in the opening in the tumbler.

In testimony that I claim the foregoing 35 as my own, I have hereto affixed my signature in the presence of two witnesses.

MORRIS J. LOVETT.
